DEVICE FOR OBTAINING AN UPWARD LUBRICANT CIRCULATION IN SPINNING SPINDLES

Louis Birkigt, Versoix, near Geneva, Switzerland, assignor to Society "Hispano-Suiza (Suisse)," S. A., Geneva, Switzerland, a society of Switzerland

Application March 6, 1952, Serial No. 275,095

Claims priority, application Luxembourg March 7, 1951

1 Claim. (Cl. 184—13)

1

The present invention relates to devices for obtaining an upward circulation of lubricant in spinning spindles driven through a worm and worm wheel gear located above an oil bath.

The chief object of my invention is to provide a device of this kind which is better adapted to meet the requirements of practice than those used for the same purposes up to the present time.

According to my invention, this device essentially comprises a rotating tube, of substantially vertical axis, turning together with a spindle and surrounding it coaxially at a distance therefrom, this tube having its lower end immersed in the oil bath, this lower end being surrounded, at a small distance therefrom, by a fixed cup-shaped part of the bottom of which is provided with a hole located opposite the bore of said tube and of smaller area than the cross section of said bore, whereby, when the tube is rotated at a sufficient speed, liquid rises along the inner wall thereof.

Preferred embodiments of my invention will be hereinafter described with reference to the accompanying drawings, given merely by way of example, and in which the figure is a vertical axial section view of a spinning spindle provided with a device according to my invention.

The drawing shows the lower part of a spinning spindle mechanism provided with a lubricating device according to my invention. Said mechanism includes a bobbin carrying spindle 5 resting, at its lower end, in a journal member 6 capable of slight displacements in the support of the mechanism and subjected to the action of centering means constituted in this construction by a spring 7. This spindle 5 extends with some play through a tube 1 coaxial therewith and with which it is coupled through means (not shown) allowing for slight oscillatory displacements of spindle 5 with respect to tube 1. Rotation movement is imparted to spindle 5 by means of a worm wheel 3 journaled about a horizontal axis in the casing 8 of the mechanism and meshing with a worm 4 fixed on tube 1 coaxially therewith.

In order to provide such a mechanism with a lubricating device according to my invention, I provide, at the bottom of casing 8, an oil bath H the level of which is located above the bottom end of tube 1 and I surround this end of tube 1 with a fixed cup-shaped part 2, for instance, secured against a shoulder of casing 8 by the external ring of the ball bearing 9 in which tube 1 is journaled.

The bottom of this cup-shaped part 2 is provided with a hole o of a diameter smaller than the inner diameter of tube 1 but greater than the diameter of spindle 5 at the level of this hole, so as to leave an annular interval for the flow of oil between the inner wall of said orifice o

and said spindle 5. Oil passing upwardly through this annular interval ascends along the inner wall of tube 1 in the form of a film f the thickness of which decreases upwardly.

This upward stream of oil may be used in particular for the following purposes:

To lubricate the region where worm wheel 3 and worm 4 are in tangential contact with each other, a radial passage 16 being provided for this purpose in the wall of tube 1; and

To lubricate an upper bearing (not visible in the drawing) in which spindle 5 is guided.

The device according to my invention has the two important advantages of being very simple and reliable and of working irrespective of the direction of rotation of the spindle.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claim.

What I claim is:

A lubricating device for a spinning spindle mechanism including a spindle and a worm and worm wheel gear for driving said spindle, which device comprises, in combination, a casing the bottom of which forms a chamber containing an oil bath, a tube coaxial with the worm and rigid therewith, the lower end of said tube being immersed in said oil bath, said tube coaxially surrounding said spindle with an annular play, and a cylindrical cup-shaped part fixed with respect to said casing and surrounding the lower end of said tube at a small distance therefrom, the cylindrical wall of said part extending to a level above that of said bath and the bottom of said part being provided with a hole, of a diameter greater than the diameter of said spindle at this level and smaller than the inner diameter of said lower end of said tube.
